HAT MANUFACTURE

Evan Ross Anderson, Irvington-on-Hudson, N. Y.

Application July 21, 1937, Serial No. 154,730

9 Claims. (Cl. 19—148)

My invention relates to a system and apparatus for forming felt hat bodies. It has been found very desirable to carry on this work under conditions of uniform temperature and moisture in order to control the quality of the product. On this account the workers are subject to most uncomfortable conditions of heat and humidity. They are also subject to the hazards of mercurial poisoning which comes from the carressing of the fur. The above conditions not only seriously interfere with their efficiency but are detrimental to their health. It has been found most difficult to maintain uniformity of control because of the fact that where such a large volume of air is being taken out of the room itself it is impossible to control air currents within the room and this materially affects the lay of the fur on the cone.

I have accordingly sought to establish a system and apparatus so designed as to eliminate discomfort and hazard to the worker and at the same time keep down the cost of equipment and operation and produce high quality articles.

In its most economical arrangement the improved system contemplates the use of a common plenum chamber from which the properly conditioned air is fed to a number of independently operable forming machines. Air is drawn from the wet process room of the factory through the sizing machines where it picks up exhaust steam and water vapor. This humidified air is drawn through a collector drum where it is regulated automatically from the control in the plenum chamber so as to produce a uniform controlled condition.

This air may be diverted into an exhaust duct to the outside atmosphere when not needed. A supplemental supply of steam may be provided for emergency purposes when the sizing machines are shut down or their output inadequate to the demands of the formers. In case the moisture content is too high, drier air may be taken from outside air. A uniform condition is maintained in the entire plenum chamber so that all the formers will receive the same uniform supply. Any suitable type of feeder and former may be employed. The conditioned air is fed individually to the formers and the lay of the fur on the cones is controlled by regulating the admission of air to the sides of the former domes. Each former is provided with a fan for exhausting the air from the inside of its cone and discharging it into the exhaust duct by which it is led to a settling chamber for removing dust and excess fur. The cleaned air is then discharged to the atmosphere.

The drawings show diagrammatically one arrangement of apparatus for the improved system.

Fig. 1 is a vertical sectional view of the principal elements.

Fig. 2 is a plan view showing one layout of formers together with adjacent sizing machines which provide the steam vapor required.

Each forming machine has a casing or dome 5 with a cone 6 of any suitable type. The fur is fed into the casing by any suitable type of feeder 7 which discharges into the former through an opening 8 above the cone. Any number of these formers may be installed in the forming room 9 in any suitable arrangement.

The conditioned air supply for the formers is derived from the plenum chamber 10 which extends above the battery of formers and may form a sort of hollow or false ceiling of the room. The upper ends of the casings 5, 5 are extended to the plenum chamber. Each former preferably has adjustable doors 11 at the sides of the dome adjacent the cone. The moisture laden warm air is withdrawn from the sizing machines 14 through ducts 15 and collector housing 16 by means of a fan 17 and forced through duct 18 to the plenum chamber 10.

This duct 18 may have a plurality of outlets 19 leading into the chamber 10. The passage of the air from the fan to the plenum duct may be controlled by a valve or damper 20. The exhaust from the fan may be by-passed or diverted to the roof or outside atmosphere through a valve or damper 21. The collector housing 16 may be drained through the outlet 22. A supplementary supply of steam or moist warm air may be admitted to the plenum chamber 10 from a nozzle or inlet 23. Dry air may be admitted to the plenum chamber through a controlled inlet 24. Suitable controlling apparatus 25 of conventional form preferably of the indicating or of the recording type may be used. This controlling apparatus 25 opens and closes the dampers 20, 21 or 24 in any well known manner to increase or decrease the moisture content of the air introduced to the plenum chamber.

Each former is provided with an exhaust fan 30 which discharges air into the exhaust duct 31 and the exhaust chamber 32 from which the air passes to the cleaner (not shown).

The proportions of the plenum chamber and ducts will depend upon the type and number of formers used. Resistance to the flow of air must be low for successful operation. Cross air currents in the former casing should be avoided except as set up purposely in the machine for its special purpose.

In a typical installation a one horse-power fan serves to take the exhaust steam from the sizing machine and deliver it to the plenum chamber. Each former has a twenty (20) horse-power fan which will handle about 6,000 cubic feet of air per minute.

From the foregoing it will be seen that the actual operation of the formers is conducted as usual but that properly conditioned air is supplied to each former chamber wholly independently of the condition existing in the work room. As a consequence working conditions are improved tremendously since no air required in the normal process is permitted outside of the ducts or machines. Workers can open windows and doors and make themselves comfortable without affecting machine operation. In fact the air in the work room may be independently conditioned without affecting the felting operation.

This system also makes it possible to safely use exhaust steam from processes which may produce steam which is contaminated with fumes that would be undesirable for the workers to be subjected to.

Actual operation of the improved process or system has demonstrated that a uniform high grade product can be turned out under ideal working conditions and without any increase in cost. The initial investment is small and the operating cost is insignificant. The steam from the wet process is usually thrown away but by my system is used to provide the necessary moisture for the felting process.

This process avoids the excess of moisture frequently found in other machines and reduces to a minimum dags, or lumps formed by fur matting on the former dome walls. These dags subsequently break off and attach themselves to the hat being formed which often makes it a "reject".

Cleanout time and frequency of cleaning have been greatly reduced and production has been increased over other methods as much as fifty percent by the use of this system.

I claim:

1. Hat forming apparatus comprising, a room, a plurality of formers in said room, a common source of conditioned air for all the formers conditioned independently of the air of the room which the workmen breathe, means for feeding fur independently into the various formers and means for withdrawing air from the formers independently of each other and for conveying substantially all said withdrawn air to a point remote from the formers and for discharging said air at said remote point, whereby said conditioned air is excluded from mixture with the air of said room, breathed by said workmen.

2. Hat forming apparatus comprising, a plurality of formers, a plenum chamber extending above the formers for furnishing temperature controlled air for all the formers independently of the air which the workmen breathe, means for feeding fur into the various formers, means for withdrawing air from the independent formers and means for positively excluding said temperature controlled air from entering into and mixing with the air breathed by said workmen.

3. Hat forming apparatus comprising, a former room, a plurality of formers in said room, means for supplying temperature controlled air from a wet process room to all the formers independently of the air of the former room, means for feeding fur independently into the various formers and means for withdrawing air from the formers said last mentioned means being separated from the air circumambient of the formers, whereby said withdrawn air is kept discrete and separate from said circumambient air.

4. Hat forming apparatus comprising, a plurality of formers, a common source of air for all the formers independent of the air surrounding the former, means for controlling the temperature of and humidifying said common source of air independently of the condition of the surrounding air, means for feeding fur into the various formers and means for withdrawing air from the formers.

5. Hat forming apparatus comprising, a room, a plurality of formers in said room, a sizing room, a plenum chamber above the formers receiving humidified air from the sizing room independently of the air of the former room and discharging it into the formers, means for feeding fur into the various formers with the humidified air and means for withdrawing air from the formers.

6. In a hat forming system the combination with the sizing machines and the forming machines of a collector housing, a fan for withdrawing air and steam from the sizing machines, a plenum chamber receiving air and steam from the collector housing, means for regulating the temperature and humidity in the plenum chamber, means for delivering the conditioned air to the forming machines from the plenum chamber, and means for exhausting the air from the forming machines.

7. In a hat forming system the combination with the sizing machines and the forming machines of a collector housing, a fan for withdrawing air and steam from the sizing machines, a plenum chamber receiving air and steam from the collector housing, means for providing auxiliary supplies of steam and of unconditioned air to the plenum chamber, means for delivering the conditioned air to the forming machines from the plenum chamber, and means for exhausting the air from the forming machines.

8. In a hat forming system, a room, a plurality of forming machines in said room, a plurality of air intakes for said forming machines, a plenum chamber above said machines, means for furnishing air to said chamber, means for controlling the degree of humidity of said furnished air, means for feeding the humidified air from said chamber to said machines independently of and without affecting the air of said room, means for feeding fur to said machines and means for exhausting air from said machines, all said air transporting means operating so as to keep said humidified air from entering said room, so that the air of said room will be free from admixture of said humidified air.

9. Hat forming apparatus including a work room, two discrete air systems, hat formers located at and forming substantially the sole means by which air can pass from one system to the other system, means for humidifying and controlling the temperature of an air supply, means for supplying said controlled air to one of said air systems, means for removing the controlled air from the other of said systems, after said air has passed through said formers, said air systems including a plurality of ducts for the transportation of said controlled air, and said ducts constituting at least a portion of the walls of both said air systems, whereby controlled air may be both supplied from and discharged to points remote from the vicinity of said formers and whereby said controlled air is excluded from said work room.

EVAN ROSS ANDERSON.
